UNITED STATES PATENT OFFICE.

WILLIAM M. WELLING, OF NEW YORK, N. Y.

DESIGN FOR A CHECK OR COUNTER.

SPECIFICATION forming part of Design No. 18,122, dated February 28, 1888.

Application filed December 16, 1887. Serial No. 258,141. Term of patent 7 years.

To all whom it may concern:

Be it known that I, WILLIAM M. WELLING, of the city and State of New York, have invented or produced a new Design for Checks or Counters, of which the following is a specification.

Counters for numbers and letters and checks for clothing and for payments at restaurants, &c., have heretofore been designed of various ornamentalations.

My design relates to the ornamentation of the surface of the check, regardless of any letter, number, or character that may or may not be upon the surface in addition to my design.

15 In the accompanying drawings, Figure 1 is a side view of a check with my design thereon, and Fig. 2 is a section of the same.

The check is circular and flat; and my design consists of the design of a circular figure 20 having undulating outlines and crossing compound curved lines, as shown at *c*, in representation of a circular and endless coil of rope, there being circular lines around outside and 25 inside the figure, a flat annular surface outside the circular design, and a flat surface inside

the same, both on the same plane. This ornamental design is shown in relief below the flat surfaces *d e* and within the circular recesses *a b* around the raised figure *c*. This ornamental design is shown at both sides of the check, 30 as indicated in Fig. 2, and the lines thereof may be in contrasting colors to the surface of the check, or the contrast may result from the lines being recessed.

I claim—

35 The ornamental design, as herein represented, for the surface of a check, consisting in the design of the circular figure having undulating outlines and compound curved diagonal crossing lines in representation of a circular 40 coil of rope, a circular line outside and inside the said figure, and the flat annular surface outside and the flat surface inside the figure on the same plane, substantially as represented.

Signed by me this 14th day of December, 45 1887.

WM. M. WELLING.
